UNITED STATES PATENT OFFICE

170,787

HOOK FOR A TROUSER WAISTBAND

Herbert Howard Wood, Birmingham, England,
assignor to Thomas Walker Limited, Birmingham,
England

Application January 27, 1953, Serial No. 23,307

Claims priority, application Great Britain
August 1, 1952

Term of patent 14 years

(Cl. D17—1)

To all whom it may concern:

Be it known, that I, Herbert Howard Wood, a subject of the Queen of Great Britain, residing at St. Paul's Square, Birmingham 3, England, have invented a new, original, and ornamental Design for a Hook for a Trouser Waistband, of which the following is a specification, reference being had to the accompanying drawing, forming part thereof.

I claim:

The ornamental design for a hook for a trouser waistband.

HERBERT HOWARD WOOD.
